(57) **CLAIM**

The ornamental design for a lock lever for walking stick, as shown and described.

DESCRIPTION

FIG. 1 is a perspective view of a lock lever for walking stick of the claimed design.

FIG. 2 is a front view of the lock lever for walking stick of FIG. 1.

FIG. 3 is a rear view of the lock lever for walking stick of FIG. 1.

FIG. 4 is a left side view of the lock lever for walking stick of FIG. 1.

FIG. 5 is a right side view of the lock lever for walking stick of FIG. 1.

FIG. 6 is a top plan view of the lock lever for walking stick of FIG. 1.

FIG. 7 is a bottom plan view of the lock lever for walking stick of FIG. 1.

FIG. 8 is a perspective view of the lock lever for walking stick of FIG. 1 in an alternate configuration with its lock lever lifted.

FIG. 9 is a bottom perspective view of the lock lever for walking stick of FIG. 1.

FIG. 10 is a rear perspective view of the lock lever for walking stick of FIG. 2; and,

FIG. 11 is a cross sectional view as taken through 11-11 of the lock lever for walking stick of FIG. 10.

The “DAC” logo in FIGS. 1, 6 and 8 is a registered trademark of Dongah Aluminum Corporation (DAC). The thin lines in the FIG. 4 depict the shapes of three-dimensional surface. The broken lines are shown for the purpose of illustrating portions of the lock lever for walking stick that form no part of the claimed design.

1 Claim, 8 Drawing Sheets
